(57) **CLAIM**

The ornamental design for a pitching net, as shown and described.

DESCRIPTION

FIG. 1 is a top, front, right side perspective view of a first embodiment of the pitching net.

FIG. 2 is a front elevation view of the first embodiment.

FIG. 3 is a rear elevation view of the first embodiment.

FIG. 4 is a left side elevation view of the first embodiment.

FIG. 5 is a right side elevation view of the first embodiment.

FIG. 6 is a top plan view of the first embodiment.

FIG. 7 is a bottom plan view of the first embodiment.

FIG. 8 is a top, front, right side perspective view of a second embodiment of the pitching net.

FIG. 9 is a front elevation view of the second embodiment.

FIG. 10 is a rear elevation view of the second embodiment.

FIG. 11 is a left side elevation view of the second embodiment.

FIG. 12 is a right side elevation view of the second embodiment.

FIG. 13 is a top plan view of the second embodiment.

FIG. 14 is a bottom plan view of the second embodiment.

FIG. 15 is a top, front, right side perspective view of a third embodiment of the pitching net.

FIG. 16 is a front elevation view of the third embodiment.

FIG. 17 is a rear elevation view of the third embodiment.

FIG. 18 is a left side elevation view of the third embodiment.

FIG. 19 is a right side elevation view of the third embodiment.

FIG. 20 is a top plan view of the third embodiment; and,

FIG. 21 is a bottom plan view of the third embodiment.

The broken lines in the drawings are for the purpose of illustrating portions of the pitching net and form no part of the claimed design.
